UNITED STATES PATENT OFFICE.

CHARLES BAUMANN, OF PHILADELPHIA, PENNSYLVANIA.

SEWING-MACHINE TRIMMER.

SPECIFICATION forming part of Letters Patent No. 618,977, dated February 7, 1899.

Application filed January 28, 1898. Serial No. 668,364. (No model.)

To all whom it may concern:

Be it known that I, CHARLES BAUMANN, a citizen of the United States, residing at Philadelphia, in the county of Philadelphia and 5 State of Pennsylvania, have invented new and useful Improvements in Sewing - Machine Trimmers, of which the following is a specification.

My invention relates to trimmers which act 10 like a pair of scissors and may be readily attached to and detached from the cloth-plate of a sewing-machine.

The object of my invention is to provide a simple and efficient trimmer adapted to trim 15 the edges of fabrics after they have been sewed together and be set with relation to the needle so as to leave seams of any width; and a further object is to provide means by 20 which the trimmer may be easily set, attached, or removed from the machine.

The invention consists of a trimmer comprising a bed, a guide-plate for said bed, an adjustable shearing-edge plate, a rock-shaft carrying an oscillating shearing - blade, a 25 spring adapted to press said blade against the shearing edge, an auxiliary rock-shaft having an arm by which it receives oscillatory motion from the needle-bar of the machine, and a set of gear-wheels to transmit 30 the oscillatory movement of the auxiliary rock-shaft to the shearing-blade; and my invention further consists of the improvements hereinafter described, and pointed out in the 35 claim.

My invention will be more fully understood 40 when taken in connection with the accompanying drawings, forming part hereof, in which—

Figure 1 is a plan view of my improved 45 trimmer operated from the needle-bar of a sewing-machine. Fig. 2 is a front elevation, and Fig. 3 is a side elevation, of the said trimmer.

Referring now to the drawings for a further 45 description of my invention, A is a bed provided with journal-bearings a.

B is a plate having wedge-shaped edges, Fig 3, secured to the cloth-plate (not shown) of a sewing-machine by means of counter- 50 sunk screws.

C is the needle-bar, and c the needle, of a sewing-machine.

The bed A, having attached thereto the trimmer proper, is provided with a dovetailed groove fitting over the wedge-shaped edges of 55 the plate B and may be set by hand to any distance longitudinally with respect to the needle c to allow for various widths of seams, after which it is clamped to the plate B.

In the rear of the base or bed A is adjustably attached, by means of a dovetailed groove d and the screw d', a right-angular shearing-edge plate D, having its forward end d² projecting, as at d³, on one side and tapered on the side d⁴ for a purpose to be described. In 60 the bearings a of the bed is journaled a shaft F, on the left end of which is secured a shearing-blade E to operate in conjunction with the projection d⁵, having a shearing edge of the plate D to trim or cut the material fed by the 65 feeding device of the sewing - machine between the same. The shearing-blade E, with cutting edge e', is held in intimate contact with the shearing edge of the projection d⁵ by a coiled spring located between an adjustable washer d⁶ on the shaft F and one side of 70 a bearing a, so that the blade E and the projection d⁵, or rather their edges, when the blade is operated act as a pair of scissors. To operate this blade E, any means may be 75 provided—for instance, a cam on the main shaft and means for imparting such cam motion to the rock-shaft F; but it is preferred to avoid any superfluous parts and connect the needle-bar to the shaft F to oscillate or 80 operate the blade E. In the present instance an auxiliary shaft G is journaled above the shaft F, and an arm g' is at one end secured to the said shaft G, while the other and free 85 extremity of the arm is slotted to engage the needle-fastening device of the needle-bar C. The motion of the shaft G attained from the needle-bar C is transmitted to the rock-shaft F by gear-wheels h, h', and h². The wheel h is secured to the shaft G and the wheel h² to 90 the shaft F, while the idle-wheel h' is attached to a shaft h³, journaled also in the bearings a, so as to cause the shearing-blade E to act in the proper time with the needle c and feed 95 (not shown) of a sewing-machine.

Having thus described the nature and objects of my invention, what I claim as new, and desire to secure by Letters Patent, is—
A sewing-machine having a needle-bar, a

cloth-plate and a plate with wedge-shaped edges secured to the cloth-plate, in combination with a trimmer comprising a bed, a dovetailed groove in the under side of the bed and 5 fitted over the said plate, a milled screw adapted to clamp the bed to the said plate, a shearing-edge plate adjustably secured to the said bed, a shearing-blade coöperating with the shearing-edge plate, a shaft on which said 10 blade is fastened, journal-bearings on said bed for said shaft, an auxiliary shaft journaled in the same bearings, an arm secured with one end to the said auxiliary shaft and having its

free end slotted and adapted for connection with the needle-bar, a gear-wheel on each of 15 said shafts and an idle-wheel between the said gear-wheels, substantially as and for the purposes set forth.

In witness whereof I have hereunto set my signature in the presence of two subscribing 20 witnesses.

CHARLES BAUMANN.
